UNITED STATES PATENT OFFICE.

ELMER O. WORRICK, OF DAET, PHILIPPINE ISLANDS.

FIBER-CLEANING DEVICE.

1,274,832.

Specification of Letters Patent. Patented Aug. 6, 1918.

Application filed February 9, 1917. Serial No. 147,638.

To all whom it may concern:

Be it known that I, ELMER O. WORRICK, a citizen of the United States, residing at Daet, in the Province of Ambos Camarines, 5 Philippine Islands, have invented certain new and useful Improvements in Fiber-Cleaning Devices; and I do hereby declare the following to be a full, clear, and exact description of the invention, such as will 10 enable others skilled in the art to which it appertains to make and use the same.

My invention relates to an improved fiber cleaning device and more particularly to a device for cleaning the fiber of the abaca 15 plant from which is made what is commercially known as Manila hemp, and has for one of its objects the production of a cheap and simple hand operated device or apparatus for use upon small plantations 20 that are not of sufficient size and productiveness to justify a more complicated and expensive machine, and which device is capable of being operated by one person though not limited to this exact number of 25 operators.

A further aim of my invention is to provide a device with a decorticating tool and a co-acting operating block supported in a manner to automatically adjust itself so that 30 the decorticating tool will engage the upper surface of the operating block evenly throughout its length, and at the same time to provide novel means for mounting the operating block upon its support whereby 35 the operating block may be readily removed when unfit for use and a new operating block substituted therefor with equal degree of readiness, and to also provide means for operating the tool.

40 A further aim is to provide a compartment in the base frame of the device in which to pivotally mount the support for the operating block and to provide the compartment with means for draining therefrom any water or moisture that may collect therein and thereby cause the wooden parts to swell and destroy the efficient operation of the operating block and its support.

50 These and other objects will more fully appear as the nature of the invention is more clearly understood from the following specification, the subject matter of the claims, and the views illustrated in the accompanying drawings, in which,

Figure 1 is a side view of the complete device.

Fig. 2 is a vertical transverse sectional view on line 2—2 of Fig. 1, looking in the direction of the arrow. 60

Fig. 3 is a perspective view of the operating block, its supporting block, and the bracket for removably securing the operating block upon its supporting block.

Referring to the drawings, wherein similar reference characters denote corresponding parts throughout the several views, my invention consists of the base member 1, having secured substantially centrally at each side thereof by the screws 2, or other suitable securing means, the supporting posts 3, and also secured upon the sides of the base member 1 by the screws 4, or other suitable securing means, are the guide posts 5 positioned preferably at a point remote 70 from the rear end of the base member 1.

Formed in the upper portion of the base member 1 forwardly of the supporting posts 3 is the cut away portion 6, preferably of semi-octagonal shape in its longitudinal direction and having extending from its bottom wall downwardly through the remaining portion of the base member 1 the drain port 7. Secured upon each side of the base member 1 by the screws 8, or other suitable 80 securing means, and covering the cut away portion 6 are the side covers or plates 9.

The cut away portion 6 in the base member 1 together with the side covers or plates 9 form a compartment in which compartment is pivotally mounted and adapted to swing the supporting block 10. The supporting block 10 is provided with the transverse opening 11, through which passes the pivot pin 12, having its ends mounted in 95 the openings 13 formed in the upper portions of the side covers or plates 9. The supporting block 10 is also formed preferably of substantially semi-octagonal shape in its longitudinal direction similar to the 100 compartment 6, and is of less length and less depth than the compartment 6 to allow free swinging movement of the block 10 therein, but the block 10 is of a width slightly less than the width of the compartment 6 so that the supporting block 10 is 105 capable of swinging movement between the covers or plates 9 without frictional engagement with the inner walls of the covers or plates 9.

Secured upon the upper face of the supporting block 10 by the screws 14, or other suitable securing means, is a securing bracket. This securing bracket consists of 5 the base plate 15 provided at one side edge with the upstanding integral apertured flange 16, through which apertured flange pass the securing bolts 17 having their opposite ends projecting through the apertured removable securing plate 18 adjacent the opposite edge of the base plate 15. Secured upon the base plate 15 of the bracket and its flange 16 and securing plate 18 and clamped therebetween by the bolts 17 is the 10 operating or head block 19 provided with the upper beveled operating face 20, the operating block 19 having the securing bolts 17 passing through transverse apertures formed in the lower portion of the 15 operating block 19.

Pivots mounted in the upper portions of the supporting posts 3 and upon the pivot bolt 21 projecting therethrough is a tool carrying operating bar 22. The bar 22 has its forward end portion operating between the supporting posts or standards 3 and upon the pivot bolt 21 while its rearwardly extending end portion projects between and is guided by the guide posts 5. In the forward end portion of the bar 22 is secured by the pivot bolt 21 and the pin 23 the shank 24 of the decorticating tool 25 provided with the beveled edge 26 to provide the tool 25 with a sharp knife like edge.

35 For normally maintaining the tool 25 in operative engagement with the beveled face 20 of the operating block 19 is provided the compression spring 27 having its upper end operatively engaging the under side of the
40 tool bar 22 at a point adjacent its rear end with the opposite end of the spring 27 seated in the socket 28 formed in the upper edge of the base member 1 adjacent the rear end thereof.

45 For operating the tool bar 22 downwardly against the compression spring 27 for elevating the tool 25 above the operating block 19 the link 29 is provided, having its upper end pivotally connected to the tool bar 22 by the pin 30, or other suitable securing means, and its lower end pivotally connected through the medium of the pin 31, or other suitable securing means, to the pedal lever 32 having its rear end pivotally connected to the base member 1 through the medium of the pivot pin 33, or other suitable pivotal connection. Secured upon the forward end of the pedal lever 32 by the screws 34, or other suitable securing means, is the pedal block 35.

The operation of the device is briefly described as follows:—The operator stands at the right hand side of the device and after taking hold of one end of a stalk of the abaca plant presses the pedal block 35 down-

wardly thereby exerting a downward pull upon the tool bar 22 through the medium of the connecting link 29 and against the force of the compression spring 27 which movement of the tool bar 22 elevates the decorticating tool 25 a sufficient distance above the coöperating block 19 to enable the operator to place a stalk of the plant adjacent the end which he has grasped upon the beveled operating face 20 of the block 19 and thereafter by removing his foot from the pedal block 35 the compression spring 27 forces the rear end of the tool bar 22 upwardly and the edge 26 of the tool 25 engages the stalk, and at this juncture the operator now draws the stalk lengthwise between the operating block 20 and the decorticating tool 25 for stripping the stalk of foreign matter for cleaning the fiber thereof. While only one stalk has been referred to in setting forth the operation of the device it is to be understood that a greater number of stalks may be drawn through the device at the same time as the operator may hold one or more stalks in each hand or may provide some clamping means for holding the ends of a large number of stalks.

While I preferably form all of the parts of the device, excepting the tool 25 which is preferably formed of tool steel, the parts 95 of the bracket and its bolts which are preferably of bronze, and the spring, which is of steel, of hard wood, especially the coöperating block 19 and which block is so formed and disposed that the grain thereof extends 100 vertically so that the tool 25 will co-act with the ends of the grain of the block 19, however, I do not desire to be limited to these exact materials as any form of material or materials may be employed. 105

From the foregoing it will be seen that I have produced a simple, cheap and efficient fiber stripping device embodying novel features of construction and advantages, a particular novel feature residing in the manner of mounting the coöperating block 19 so that its operating face 20 will be automatically brought into parallelism with the operating portion of the decorticating tool 25 thereby adding to the efficiency of the operation of the device. 110 115

I desire it to be also understood that I am not limited to the use of the specific form of tool shown in the drawings as this tool, being removably secured in the end of the tool bar 22, may be removed and substituted by a tool of different construction. 120

Having described my invention, what I claim as new and desire to secure by Letters Patent, is:—

1. The combination of a decorticating tool, and a head block coöperating with said tool; with means to cause said head block to swing to align itself with said tool.
  2. The combination of a decorticating tool,

- and a head block coöperating therewith; with means to provide for the automatic swinging of said head block to aline said block with said tool.
3. The combination of a decorticating tool, and a head block coöperating with said tool; with means for pivotally supporting said head block whereby to cause the automatic swinging adjustment of said block relative 10 to said tool.
4. In a device of the character specified, the combination of a decorticating tool, and means for actuating said tool; with a longitudinally swinging head block for coöperating with said tool evenly throughout its 15 length.
5. In a device of the character specified, the combination of a decorticating tool, means for actuating said tool, and a head 20 block coöperating with said tool; with means for pivotally supporting said head block centrally and transversely of its longitudinal direction for causing said head block to automatically swing to adjust itself when 25 engaged by said tool whereby to cause contact between said tool and said head block evenly throughout their lengths.
6. In a device of the character specified, the combination of a decorticating tool, 30 means for actuating said tool, a head block coöperating with said tool, a support for said head block pivotally supported centrally and transversely of its longitudinal direction to provide for the automatic 35 swinging of said head block relative to said tool, and a bracket upon said support for detachably securing said head block thereon.
7. In a device of the character specified, the combination with a base member, a tool 40 operatively mounted upon said base member, means for actuating said tool, a compartment formed in said base member beneath said tool, cover plates for said compartment, a supporting block swingingly mounted upon
- said cover plates and within said compartment, an elongated channeled bracket secured upon said supporting block, and a head block removably secured in said bracket and coöperating with said tool, whereby to provide for the automatic swinging of said 45 head block to coact with the entire operating surface of said tool.
8. In a device of the character specified, the combination with an elongated horizontally disposed base member, a compartment 50 in proximity to one end of said base member, a head block swingingly mounted in said compartment and in the longitudinal direction of said base member, a pair of spaced supporting posts upon said base member at 55 one side of said block, a bar pivotally mounted upon and between said supporting posts in proximity to one of its ends, a tool secured in this end of said bar for coöperating with said head block, an expansion 60 spring interposed between said base member and the free end of said bar at the end of said base member remote from said compartment for normally holding said tool in operative position with respect to said head 65 block, a foot lever having one end pivotally mounted upon a side of said base member, and a connection between said foot lever and said bar at a point between the pivotal point 70 of said bar and said expansion spring, whereby upon the downward pressure of said foot lever the free end of said bar will be forced downwardly against said expansion spring for elevating said tool above said head block.
- In testimony whereof I have signed my name to this specification in the presence of 75 two subscribing witnesses.

ELMER O. WORRICK.
